UNITED STATES PATENT OFFICE

JAMES C. GRIFFIN, OF ERIE, PENNSYLVANIA, ASSIGNOR TO GRIFFIN MANUFACTURING COMPANY, OF ERIE, PENNSYLVANIA, A CORPORATION OF PENNSYLVANIA

DOOR LATCH

Application filed January 2, 1929. Serial No. 329,883.

The present invention provides a door latch of simple and efficient construction, one that may be readily reversed as to the sides of the door, one in which the fulcrum point 5 of the actuating bar is at the same face of the door as the latch bar, and one in which the latch bar may be readily locked through the locking of the actuating bar. Features and details of the invention will appear from 10 the specification and claims.

A preferred embodiment of the invention is illustrated in the accompanying drawing as follows:—

Fig. 1 shows a vertical section of the latch. 15 Fig. 1a a front view of the handle plate. Fig. 2 a section on the line 2—2 in Fig. 1. Fig. 3 a similar view with the latch bar reversed.

Fig. 4 is a perspective view of the door 20 catch.

Fig. 5 a section on the line 5—5 in Fig. 1 with the latch unlocked.

Fig. 6 a similar view with the latch locked.

Fig. 7 an enlarged sectional view of the 25 locking latch on the line 7—7 in Fig. 5.

1 marks the latch handle. This is provided with a securing end plate 2 struck up from the material of the handle and a screw 3 extends through this end 2 into a door 4. 30 A handle plate 5 is formed on the upper end of the handle. It is secured to the door by opposingly placed screws 6 which extend through openings 7 in the handle plate 5. An actuating bar 8 extends through an opening 9 in the handle plate 5. The actuating bar has an off-set 10 which while it permits of the insertion of the bar through the handle plate when the handle is detached from the door locks it against removal from the 40 plate with the handle in place. The actuating bar has a thumb piece 11 at one end and a finger piece 12 at the opposite end, and is fulcrumed on the handle plate. It extends through an opening 13 in the latch bar 14. The latch bar has a perforation 15 through which one of the screws 6 extends. The latch bar extends through an opening 16 in a surrounding shoulder, or rib 17 at 45

50 the base of the handle plate 5.

A door catch 18 is adapted to receive the latch bar. It has an inclined point 19 and catch notches 20 at opposite sides of the point 19. This makes the catch available for either side of the door.

The handle plate 5 extends outwardly from the face of the door a sufficient distance to so place the fulcrum for the actuating bar as to give the actuating bar the desired movement for actuating the latch bar. There are two oppositely placed openings 16 through which the latch bar may extend and the latch bar is simply a flat plate. All that is necessary to reverse the latch for opposite sides of the door is to secure the latch plate 14 with one or the other of the screws 6 as the side of the door will indicate. This with the reversing catch makes the latch as a whole completely reversible.

The actuating bar extends through an opening 21 in an escutcheon 22 on the opposite face of the door from the plate 5. The escutcheon is struck up from a piece of sheet metal with a surrounding rib 23 and is secured to the door by screws 24. These screws extend through openings 25 which are cut in the metal, the openings being struck up forming countersunk walls 26 for receiving the screws. A locking finger 27 is pivotally mounted on the upper countersunk wall 26, 75 this wall being headed over at 26a to secure the finger in place. The upper end of the finger has an extension 28 which projects through an opening 29 in the rib 23 and this has a turned out portion 28a forming a handle by means of which the finger may be readily operated. A finger end 31 is adapted to be swung over the actuating bar 8 so as to lock that bar in its normal latched position, as shown in Fig. 1, and the locking of 80 this bar locks the latch bar 14 in that the walls of the opening 13 engage both the bottom and top of the actuating bar so that the latch bar is locked with the actuating bar and moves with it, or is locked against movement with it. A friction washer 32 is arranged under the locking finger 27 and around the countersunk wall 26 and this yieldingly exerts sufficient frictional resistance to movement to the finger to lock the finger either in 85 90 95 100

a locking position, or an unlocked position as against any ordinary door jars.

What I claim as new is:

1. In a door latch, the combination of a latch bar; a handle plate over the latch bar; an actuating bar fulcrumed on the handle plate and having connection with and operating the latch bar, said connection compelling the latch bar to move with the actuating bar in both directions; an escutcheon adapted for attachment at the side of a door opposite the handle plate through which the actuating bar extends, said escutcheon having screw-receiving openings therein with a counter-sunk wall; and a locking finger pivotally mounted on the counter-sunk wall, said finger being adapted to be swung into and out of locking engagement with relation to the actuating bar.
  2. In a door latch, the combination of a latch bar; a handle plate over the latch bar adapted to be grasped by an operator to pull the door toward him; and an actuating bar having a fulcrum on the handle plate spaced outside the latch bar, said actuating bar having a thumb plate adapted to be actuated by an operator grasping the handle plate and to actuate the latch bar by a downward movement of the thumb plate, said actuating bar having an inward extension adapted to extend through a door and to be actuated from the opposite side of the door from the latch bar by an upward movement of the extension; and means acting on the inner end of the extension of the actuating bar locking the actuating bar.
  3. In a door latch, the combination of a reversible latch bar; a handle plate housing the latch bar and which may be grasped by an operator in opening the door, said housing having opposed openings for the latch bar permitting the reversal of said latch bar; and means adapted to secure the latch bar in position on the handle plate so that the latch bar may extend through either opening of the handle plate.
  4. In a door latch, the combination of a reversible latch bar having a pivot opening; a handle plate housing the latch bar, said handle housing having opposed openings for the latch bar permitting the reversal of the latch bar and having two screw openings; and a screw in each of said openings, one of the screws extending through the pivot opening said screws securing the plate and the latch bar in operative position.
  5. In a door latch, the combination of a latch bar; a handle plate over the latch bar forming a housing for the latch bar, said handle plate being adapted to be grasped by an operator to pull the door toward him; means adapted to reversibly secure the latch bar pivotally on the handle plate; and an actuating bar having a connection with the latch bar compelling a movement of the latch bar with the actuating bar in both directions and having a fulcrum on the handle plate outside the latch bar, said actuating bar hav-
- ing a thumb plate adapted to be actuated by an operator grasping the handle plate and to actuate the latch bar by a downward movement of the thumb plate, said actuating bar having an inward extension adapted to extend through a door and to be actuated from the opposite side of the door from the latch bar by an upward movement of the extension.
6. In a door latch, the combination of a latch bar; a handle plate over the latch bar adapted to be grasped by an operator to pull the door toward him; an actuating bar having a connection with the latch bar compelling a movement of the latch bar with the actuating bar in both directions and having a fulcrum on the handle plate spaced outside the latch bar, said actuating bar having a thumb plate adapted to be actuated by an operator grasping the handle plate and to actuate the latch bar by a downward movement of the thumb plate, said actuating bar having an inward extension adapted to extend through a door and to be actuated from the opposite side of the door from the latch bar by an upward movement of the extension; and means acting on the inner end of the extension of the actuating bar locking the actuating bar.
7. In a door latch, the combination of a latch bar; a handle plate over the latch bar adapted to be grasped by an operator to pull the door toward him; an actuating bar having a connection with the latch bar compelling a movement of the latch bar with the actuating bar in both directions and having a fulcrum on the handle plate spaced outside the latch bar, said actuating bar having a thumb plate adapted to be actuated by an operator grasping the handle plate and to actuate the latch bar by a downward movement of the thumb plate, said actuating bar having an inward extension adapted to extend through a door and to be actuated from the opposite side of the door from the latch bar by an upward movement of the extension; and means acting on the inner end of the extension of the actuating bar locking the actuating bar.
8. In a door latch, the combination of a latch bar; a handle plate over the latch bar adapted to be grasped by an operator to pull the door toward him; an actuating bar having a connection with the latch bar compelling a movement of the latch bar with the actuating bar in both directions and having a fulcrum on the handle plate spaced outside the latch bar, said actuating bar having a thumb plate adapted to be actuated by an operator grasping the handle plate and to actuate the latch bar by a downward movement of the thumb plate, said actuating bar having an inward extension adapted to extend through a door and to be actuated from the opposite side of the door from the latch bar by an upward movement of the extension.

the opposite side of the door from the latch bar by an upward movement of the extension; an escutcheon through which the actuating bar extends, said escutcheon having a pivot wall struck up in it, said wall forming a screw opening for a securing screw and a locking finger mounted on the wall and adapted to be swung into and out of locking engagement with the actuating bar.

10 In testimony whereof I have hereunto set my hand.

JAMES C. GRIFFIN.
